UNITED STATES PATENT OFFICE.

ANDREW LILLIQUIST, OF SYRACUSE, NEW YORK.

WIRE-FINISHING MACHINE.

1,156,299.

Specification of Letters Patent.

Patented Oct. 12, 1915.

Application filed February 24, 1912. Serial No. 679,608.

To all whom it may concern:

Be it known that I, ANDREW LILLIQUIST, of Syracuse, in the county of Onondaga and State of New York, have invented a certain 5 new and useful Wire-Finishing Machine, of which the following is a specification.

This invention has for its object the production of a machine for finishing wires or rods by polishing the same or grinding them 10 to a certain gage, and the invention consists in the combinations and constructions hereinafter set forth and claimed.

In describing this invention reference is had to the accompanying drawings in which 15 like characters designate corresponding parts in all the views.

Figure 1 is a plan, partly in section and partly broken away, of one embodiment of my invention. Figs. 2 and 3 are opposite 20 end elevations of parts seen in Fig. 1. Fig. 4 is a front elevation of this machine. Fig. 5 is a sectional view on line "A—A", Fig. 1. Figs. 6, 7 and 8 are enlarged sectional views taken, respectively, on lines "6—6," "7—7" 25 and "8—8" Fig. 5. Fig. 9 is an enlarged sectional view of the lower end of one of the wire holding members. Figs. 10 and 11 are enlarged detail views of the micrometers associated with certain adjustments of my 30 machine.

This machine comprises, generally, abrading means, and means for simultaneously rotating and feeding the wire to the abrading means. Usually one of said means is so supported that it can be adjusted toward and from the other of the means for determining the gage of the wire and also for taking up for the wear of the abrading means.

In the illustrated embodiment of my invention the abrading means comprises a rotating member as a grinding wheel, and the rotating and feeding means comprises a rotating element arranged with its periphery in position to engage and rotate and feed 40 the wire, said element being arranged with its axis extending in the direction of the feeding movement and with its periphery engaging the wire so that points on the portion of the periphery of said element in engagement with the wire advance to some extent, during the turning of said element; in the direction of feeding of the wire, in other words, in a direction spirally relatively to an axis parallel to the axis of the wire; and owing to the frictional engagement of such 50 element with the wire, the wire is caused to

advance as well as rotate. Preferably the rotating element is arranged with its axis inclined at a small angle crosswise of the axis of the wire.

In this embodiment of my invention the abrading member is fixed from movement, as a unit, toward and from the wire, while the rotating and feeding means is movable as a unit toward and from the working face of 65 the abrading member.

1 is the frame or bed which may be of any desirable form, size and construction.

2 is the abrading member here shown as a wheel having an axle 3 journaled in suitable 70 bearings 4 mounted on the bed or frame 1, suitable means by which the wheel can be connected or disconnected from power being mounted on the axle, as fixed and loose pulleys 5, 6.

7 is a carriage movable on the frame or bed 1 toward and from the abrading member, the bed being formed with raised ways 8, Figs. 4 and 7, near its opposite ends which coact with guides 9 on the frame, the guides 20 running on the upper face of the bed. The carriage 7 is additionally guided in its movement by rods 10 engaging suitable means on the carriage 7. The carriage 7 also comprises a plurality of upright supports or 85 bearing frames 11 located on opposite sides of the abrading member, for supporting the rotating elements as hereinafter described.

In this embodiment of my invention, I 90 preferably use rotating and feeding means located on opposite sides of the abrading member, the means on each side usually comprising a pair of rotating elements preferably in the form of cylinders or rollers 12, 13 arranged on opposite sides of the path 95 of the wire 14 and arranged with their axes extending in the direction of the wire, such axes being arranged in parallel planes, as vertical planes, in this embodiment of my invention, and as being inclined in opposite directions out of a plane, as a horizontal plane, containing the axis of the wire 14 and meeting the first-mentioned plane at a right angle, the rollers being preferably opposed to each other so that the intermediate 100 portions of their axes intersect said horizontal plane. The inclined arrangement of the rollers is clearly seen in Fig. 4.

The rollers or cylinders 12, 13 are provided with axles 15, Fig. 6, journaled in 110 bearing blocks 16 which are supported by, and adjustable relatively to, the frames 11,

and each block is held in its adjusted position by a set screw 17. The adjustment of the bearing blocks are in the same direction as that of the carriage 7, and is determined by screws 18 associated respectively with the blocks carried by each frame 11.

The sliding movement of the carriage 7 is effected by a screw 19 located substantially centrally of the frame or bed 1 and having 10 a micrometer 20 associated therewith.

The carriage 7 is held in its adjusted position by suitable clamping means consisting of a screw 21 depending therefrom through the bed or frame 1 and having a clamping 15 nut 22 turning on its lower end against a suitable plate or washer 23 bearing against the lower face of the bed or frame 1.

The elements or cylinders 12 and 13 are actuated in any suitable manner, and, as here 20 shown, a main driving shaft 24 is journaled in suitable bearings in the carriage 7 and is provided with gears 25 at opposite ends of the carriage 7, each of the gears 25 meshing with one of a pair of idlers 26 which mesh 25 respectively with pinions 28 mounted on the corresponding ends of the axles 15 of each pair of gears 12, 13. The shaft 24 is also provided with suitable means by which power can be applied thereto, as the pulley 30 29, which may be connected or disconnected to the shaft 24 by clutch mechanism operated by a handle 30. My machine is also provided with suitable means for engaging the wire at points separated from one another 35 approximately ninety degrees for holding the wire to the abrading member, and for holding the wire between the rollers 12, 13.

The means for holding the wire to the working face of the abrading member, is 40 adjustable to hold different sizes of wire, and comprises parts having faces arranged at an angle to each other, and in the angle of which the wire is held, as seen in Fig. 5, one part being adjustable relatively to the 45 other to conform to the size of the wire being operated on. In this embodiment of my invention, said means is adjustable vertically as a whole.

31 and 32, Fig. 5, are respectively the parts 50 of the wire holding means, said parts being in the form of plates, the plate 31 being mounted on a support or bridge 33 suitably carried by the lower cross bars of the two intermediate frames 11 of the carriage 7, and the plate 31 being adjustable vertically 55 by means of a screw 34, carried by said support 33 and held from endwise movement, and turning into a threaded socket 35 carried by the plate 31.

60 The plate 31 is guided relatively to its support 33 by means of pins 36 carried by the plate 31 and working in holes 37 in the support 33. The plate 31 provides the horizontal surface for the support of the wire 65 at the abrading member.

The plate 32 provides the vertical surface for the support of the wire at the abrading member, and is adjustable toward and from the abrading member relatively to the plate 31, by suitable means as a screw 38 carried 70 by the plate 31 in a suitable bearing 39 rising from the plate 31 in a slot 40, Figs. 1 and 5, in the plate 32, and threading in a passage in the plate 32. A suitable micrometer 41, Figs. 5 and 11, is associated with the carriage for exactly determining the amount of adjustment of the plate 32, this adjustment being determined by the size of the wire to be operated on or to be produced.

The plate 32 is held in its adjusted position by suitable clamping means consisting of a screw 42 rising from the plate 31 through the slot 40, and a clamping nut 43 turning on the screw against a suitable washer or bearing plate 44 bearing against 85 the upper face of the plate 32.

The means for holding the wire between the rollers comprises suitable members 45, as blocks spaced apart at intervals and bearing downwardly on the wire on opposite 90 sides of the abrading means, said members also holding the wire on the central wire support. Said members are formed with grooves 46 of such curvature as to receive various sizes of wire. The members 45 are 95 supported by screws 47 carried vertically by the frames 11 of the carriage 7. The wire is therefore held at two sides by the plates 31, 32 at a third side by the working face of the abrading members and at a 100 fourth side by the blocks 45.

In order to accurately position the members 45 during various adjustments of the carriage 7, the screws 47 turn through blocks 48 slidably mounted in ways 50 in the upper cross bars of the frames 11, Fig. 8. The positioning of the blocks is effected by means of projections as screws 51 extending laterally from such blocks through slots 52 in the upper bars of the frames 11. These 110 blocks are held in their adjusted positions by nuts turning on the screws against the upper face of the frame bars 11.

The wire is guided between the rollers 12, 13 in a direction lengthwise of the rollers by 115 suitable guiding means, here shown as a tube 53 movable with the carriage 7 and supported in the standard 54 rising from the carriage 7 at the outer side of the pulley 29, the tube extending above said pulley. This tube is of sufficient diameter to accommodate various sizes of wires which the machine is adapted to operate on, and is arranged with its axis alined approximately with the space between the rollers 12, 13.

In operation the screw 38 is operated to adjust the machine to the gage of the wire it is desired to produce, and the carriage 7 adjusted by means of the micrometer adjustment 19, 20 toward the abrading member,

and after the various adjustments of the rollers and wire holding means have been completed, the wire is pushed through the tube to the rollers by which it is rotated and fed crosswise of the abrader 1, the abrader 1 taking off a predetermined amount of all sides of the wire leaving the wire exactly circular in cross section and of a certain gage determined as herein explained.

10 10. What I claim is:

1. In a wire finishing machine, a bed, a rotatable abrading member supported thereby, a carriage movable upon the bed toward and from the operative face of the abrading member, means for shifting the carriage, means mounted in the carriage for feeding the element to be operated upon in a direction across the operative face of the abrading member, and additional means mounted in the carriage for holding said element in coöperative relation with the feeding means and in a predetermined position relative to said operative face of the abrading member, substantially as and for the purpose described.

2. In a wire finishing machine, a bed, a rotatable abrading member supported thereby, a carriage movable upon the bed toward and from the operative face of the abrading member, means for shifting the carriage, means mounted in the carriage for feeding the element to be operated upon in a direction across the operative face of the abrading member, and additional means mounted in the carriage for holding said element in coöperative relation with the feeding means and in a predetermined position relative to said operative face of the abrading member, said means including a part adjustable in the carriage and toward and from said operative face of the abrading member, substantially as and for the purpose specified.

3. In a wire finishing machine, a bed, a rotatable abrading member supported thereby, a carriage movable upon the bed toward and from the operative face of the abrading member, means for shifting the carriage, means mounted in the carriage for feeding the element to be operated upon in a direction across the operative face of the abrading member, and additional means mounted in the carriage for holding said element in coöperative relation with the feeding means and in a predetermined position relative to said operative face of the abrading member, said additional means including a part adjustable toward and from said operative face of the abrading member and an additional part carrying the first-named part and adjustable in a direction perpendicular to the direction of movement of the first-named part, substantially as and for the purpose set forth.

4. In a wire finishing machine, a bed, a rotatable abrading member supported there-

by, a carriage movable upon the bed, means for shifting the carriage toward and from the operative face of the abrading member, means for feeding the element to be operated upon, said means including rotary members located on opposite sides of the abrading member and mounted in the carriage and driving means therefor also mounted in the carriage, means mounted in the carriage in advance of the operating face of the abrading member for holding the element to be operated upon in a predetermined position in relation thereto, and additional holding means for said element located between the first-named holding means and said rotary member of the feeding means, substantially as and for the purpose described.

5. In a wire finishing machine, a rotatable abrading member, and means for feeding the element to be operated upon across the operative face thereof and supporting it in a predetermined relation thereto, said means including a coarse adjusting mechanism and a fine adjusting mechanism, the coarse adjusting mechanism including a carriage, and the fine adjusting mechanism including parts supported by the carriage and adjustable in the direction of movement thereof, substantially as and for the purpose specified.

6. In a wire finishing machine, a base, a carriage movably supported thereon, an abrading element, means for adjusting the carriage toward and from the operative face thereof, feeding means for feeding the element to be operated upon transversely across said operative face of the abrading member, and means for engaging said element at three points separated from one another approximately ninety degrees for holding the element while it is being operated upon, one of the engaging means being adjustable toward and from the operative face of the abrading member, and another engaging means being adjustable in a direction perpendicular to the direction of movement of the first-named engaging means, substantially as and for the purpose described.

7. In a wire finishing machine, a rotary abrading member, means for feeding the element to be operated upon across the face of said member, and means for holding said element in a predetermined relation to said face including a part movable toward and from the face, and a second part carrying the first, movable in a direction perpendicular to said direction of movement of the first and having a surface for engaging the element to be operated upon disposed at an angle and contiguous to the engaging surface of the first-named part, substantially as and for the purpose specified.

8. In a wire finishing machine, the com-

- bination of a frame, an abrading member, a carriage movable on the frame relatively to the abrading member, means for rotating the wire and feeding the same to the abrad- 5 ing member, said means comprising a pair of rotating drums on each side of the abrading member and arranged to rotate and feed the wire axially, means located near the ends of each pair of drums for 10 pressing downwardly on the wire and means in front of the abrading member for engaging the underside and the front side of the wire, intermediate of the pair of drums, substantially as and for the purpose set forth.
9. In a wire finishing machine, the combination of a frame, an abrading member, a carriage movable on the frame relatively to the abrading member, means for rotating 20 the wire and feeding the same to the abrading member, said means comprising a pair of rotating drums on each side of the abrading member and arranged to rotate and feed the wire axially, means located 25 near the ends of each pair of drums for pressing downwardly on the wire, and means in front of the abrading member for engaging the under side and the front side
- of the wire, intermediate of the pair of drums, the last-mentioned means including 30 parts adjustable vertically and horizontally to conform to the size of the wire, substantially as and for the purpose described.
10. In a wire finishing machine, the combination of a frame, an abrading member, a carriage movable on the frame toward and from the abrading member, means for rotating the wire and feeding the same to the abrading member, supports for carrying 35 said means, the supports being mounted on the carriage and adjustable on the carriage toward and from the abrading member, means for feeding the carriage, and means for adjusting the supports on the carriage, substantially as and for the purpose 40 specified.
- In testimony whereof, I have hereunto signed my name in the presence of two attesting witnesses, at Syracuse, in the county of Onondaga, in the State of New York, 50 this 23rd day of December, 1911.

ANDREW LILLJQUIST.
